UNITED STATES PATENT OFFICE.

JOHN C. EBERHARDT, OF DAYTON, OHIO, ASSIGNOR TO ANDERTON,
EBERHARDT & CO., OF SAME PLACE.

DESIGN FOR A SPOON.

SPECIFICATION forming part of Design No. 20,907, dated July 7, 1891.

Application filed June 3, 1891. Serial No. 394,964. Term of patent 7 years.

To all whom it may concern:

Be it known that I, JOHN C. EBERHARDT, a citizen of the United States, residing at Dayton, in the county of Montgomery and State of Ohio, have invented and produced a new and original Design for Spoons, of which the following is a specification, reference being had to the accompanying drawing, forming part thereof.

10 The figure is a front or upper face view of the spoon.

The leading feature of my design consists of the figure of a soldier in the uniform of a United States volunteer, with his gun in the 15 attitude of "parade rest." This figure forms the end of the handle of the spoon, as shown at section A. The intermediate or shank por-

tion of the handle (shown at section B) is in the form of a scrolled column or pedestal, upon which the soldier stands. The base of the pedestal (shown at section C) presents the configuration of a spread-eagle perched upon crossed cannon and carrying a saber in his claws. Below the cannon is a pile of cannon-balls. This section C extends over onto and 25 forms a part of the bowl of the spoon.

What I claim is—

The design for a spoon, substantially as shown and described.

JOHN C. EBERHARDT.
